UNITED STATES PATENT OFFICE.

SAMUEL K. DENNIS, OF CHICAGO, ILLINOIS, ASSIGNOR, BY MESNE ASSIGNMENTS, TO INTERNATIONAL HARVESTER COMPANY, A CORPORATION OF NEW JERSEY.

STRADDLE-ROW CULTIVATOR.

1,388,934.

Specification of Letters Patent. Patented Aug. 30, 1921.

Application filed April 30, 1915. Serial No. 24,946.

To all whom it may concern:

Be it known that I, SAMUEL K. DENNIS, a citizen of the United States, residing at Chicago, in the county of Cook and State of Illinois, have invented certain new and useful Improvements in Straddle-Row Cultivators, of which the following is a full, clear, and exact specification.

This invention relates to straddle row cultivators, and has for its object to improve and simplify the operation and construction of such devices, particularly the type of cultivator shown in patent to Tinsman, No. 1,025,220, May 7, 1912.

In carrying out my invention I employ in connection with a pivot pole, seat-guide cultivator a mounting for the beams whereby they are caused to move laterally in parallel relation, and an improved connection between the beams and pivot pole for moving the former laterally when the pole is angled to change the course of the cultivator, said connection being adjustable so that the beams may be moved independently of the pole and of each other.

One form which my invention may assume is exemplified in the following description and illustrated in the accompanying drawing, in which—

Figure 1 shows a vertical central sectional view of a cultivator embodying my invention;

Fig. 2 shows a fragmentary view in plan of the improved connection employed between the pivot pole and the beams;

Fig. 3 shows a detached view in elevation of said connecting means;

Fig. 4 is a plan view of the cultivator embodying my invention; and

Fig. 5 is a plan view showing the tongue angled.

Referring in detail to the drawing, it will be seen that I employ a cultivator comprising ground wheels 10, and a main frame 11, to which is pivoted at 12 a pole 13. The rear end of the pole has a sliding connection 14 with the main frame, and a seat support 15 is pivotally and slidably carried upon the arched axle 16 of the ground wheels and has its forward end pivotally connected to the rear end of the pole by means of a vertically arranged pivot bolt 17 passing through the pole and entering a pivot plate 18. This plate has upstanding ears 19, to which the seat support is pivoted for movement in a

vertical plane, the latter movement of the seat support being desirable for folding the seat over the pole. The rear end of the support 15 carries a seat member 20, which is adjustable fore and aft in the usual way. Beams 21, carrying shovels 22, or other earth working devices, are suspended at their forward ends from the frame of the cultivator each by means of a pendent bail-rod 23 carried for oscillating movement in bearings 24 arranged on the axle and forward end of the main frame. A horizontally arranged crank-rod 25, pivotally connected to the wheel spindle and adjacent beam, transmits a push motion to the beam and swings freely about its pivots to permit lateral shifting of the beam, the bail-rod acting to hold the beam in fore and aft alinement. The rear end of the bail member 23 has a slidable connection with the beam so that said beam may be adjusted vertically by means of a lever 26 or other raising device. The tool carrying beams 21 at their rear ends, are suspended from the levers 26 by links 261. These links are as usual provided with operating handles and have pivotal connections at each end respectively with the levers 26 and the beams 21. The pivotal connections are arranged to permit the beams to swing laterally around the pivots between links 261 and the upper ends of levers 26, and also to permit a longitudinal swinging motion of levers 26 and links 261 when operated to lift or lower the beams 21.

From the description thus far given it will be seen that the beams 21 will be held in alinement by the pendent bail members 23, and will always maintain their parallelism no matter what their position of lateral adjustment may be. The connections are such as to permit raising and lowering of the beams, and the operation of the pivot pole and seat guide is to change the course of the cultivator independent of the direction of travel of the draft animals.

With no connection between the movable pole or seat support and the beams, it is apparent that the ultimate object of angling the pole, which is to shift the ground tilling members laterally, will be accomplished indirectly and slowly; that is to say, the frame of the cultivator will first shift its course and the beams will thereupon trail slowly in the direction of movement of the frame. Such an operation, obviously, is not sufficiently

positive and certain to afford an accurate control of the beams. I have, therefore, provided a simple yoke connection between the pivot pole and seat support and the beams whereby, as the rear end of the pole is swung around to change the course of the machine, the beams will be positively and quickly moved in the same direction.

This connection comprises a yoke including two members 27, having their outer ends slidably and pivotally connected to the front pendent portions of the bail members 23 and projecting rearwardly and spanning the pole, where their inner ends overlap and connect with the pivot-plate 18 between the seat support and pole. The connection between the plate 18 and yoke is by means of a vertical stud 28 mounted upon the forward end of the plate in front of the pivot bolt 17, and upon this stud is fitted a clip member 29, which clip member is connected, by means of a bolt 30, to the overlapping inner ends of the yoke members. The inner ends of the yoke members are looped above the pivot bolt 30, and are again connected, by means of an adjusting bolt 31 passing through suitable openings or slots 32 formed in the ends of said yoke members.

By suitable adjustment of the bolt 31 the lower outer ends of the yoke members may be moved together or apart, swinging about the bolt 30, and in this way the relative distance between the members of the gang on which the yoke member is carried may be adjusted. The bolt 31 will also lock the yoke members so that, as the seat support is moved to swing the pole from one side to the other, the yoke, being carried thereby, will act positively to shift the shovel beams bodily laterally in rigid alinement. On account of the position occupied by the yoke member, the beams will in reality be moved farther than the rear end of the pole. This follows from the fact that the stud member 28 which carries the yoke swings about the pivot bolt 17 and receives a greater movement when the seat is shifted than does the pivot itself.

Should it be desired to discontinue the positive lateral shifting of the shovel beams, it is only necessary for the operator to remove the adjusting bolt 31, whereupon the yoke members will hinge freely and independently about the bolt 30, and the beams may then be swung laterally independent of each other. With the yoke members so adjusted the usual operation of cultivating would be to lock the pivot pole and seat, and means are provided for this purpose which, in the simplest form, comprise merely a pin (not shown) adapted to be fitted into the connection 14, locking it with the frame 11.

If the operator desires to employ the pivot pole without obtaining a positive movement of the beams, it is only necessary for him to

lift the yoke, freeing the clip member 29 from the stud 28, and the desired adjustment is accomplished. Movement of the pole will not then impart a positive and direct movement of the yoke, the latter sliding freely upon the upper surface of the pole. In this position of the yoke it may be used to take the place of the ordinary jockey arch to hold the beams in fixed relation, or may, as before indicated, be unlatched to permit free and independent swinging of the beams.

Enough of the possible uses of my invention have been mentioned to indicate the importance thereof. In the normal operation of the device with the yoke members 27 secured together at their upper ends, a lateral motion of beams 21 is effected by swinging the seat lever 15 due to pressure applied to the foot rest 211 on one of the beams. The beams swing from the pivotal connections 80 between levers 26 and links 261 and the bearings 24 of bails 23. The thrust bars 25 swing around their pivotal connections with the frame of the machine at a point near the wheel axles. The bails 23 are free to move longitudinally in their bearings 24 to permit the horizontal arc motion of thrust bars 25. The yoke members 27 may, without pivotal action, move laterally with the tool beams 21 and the adjoining ends of the seat lever and tongue, but the tool beams may be shifted laterally independently of motion of the seat lever and tongue, in which case yoke members 27 swing around bolts 30. This results in one of the yoke members sliding upwardly along the forward depending arm of one of the bails 23 while the opposite yoke member 27 moves downwardly along the forward depending arm of the remaining bail.

While I have shown and described but one form of my invention herein, it should be understood, nevertheless, that it is susceptible of modification and, therefore, many changes may be resorted to in the construction and arrangement of the several parts without departing from the spirit thereof as disclosed in the appended claims.

What I claim as new is:

1. In a wheeled cultivator, a frame, cultivator beams connected to the frame by laterally shiftable means including pendent members, a guiding member pivotally supported between its ends for lateral swinging movement on the frame, a pivot member on the forward end of the guiding member, and a yoke supported on said pivot member and having its branches slidably connected to said pendent members.

2. In a wheeled cultivator, a frame, cultivator beams connected to the frame by laterally shiftable means including pendent members, a guiding member pivotally supported between its ends for lateral swinging movement on the frame, a plate on the for-

ward end of said guiding member, provided with a vertical stud and a yoke provided with a clip pivoted on said stud and having its branches slidably connected with said pendent members.

3. In a wheeled cultivator, a frame, cultivator beams connected to the frame by laterally shiftable means including pendent members, a draft pole pivoted between its 10 ends to the front of the frame and having its rear end supported for lateral movement on the frame, a guiding member pivotally supported on the frame to the rear of said pole, a plate connected to the forward end of 15 the guiding member and connected to the rear end of said pole on a vertical pivot, and a yoke provided with a part pivotally mounted on said plate and having its branches slidably connected with said pendent members.

20 4. In a wheeled cultivator, a frame, cultivator beams connected to the frame by laterally shiftable means including pendent members, a draft pole pivoted between its 25 ends to the front of the frame and having its rear end supported for lateral movement on the frame, a guiding member pivotally supported on the frame to the rear of said pole,

a plate to which the forward end of the guiding member is horizontally hinged and 30 to which the rear end of the pole is connected on a vertical pivot, and a yoke provided with a clip engaging a vertical pin on said plate and having its branches slidably connected to said pendent members.

35 5. In a wheeled cultivator, a frame, cultivator beams connected to the frame by laterally shiftable means including pendent members supporting the front end of the beams, a rearwardly projecting guiding 40 member supported between its ends for lateral swinging movement on the frame, a plate on the forward end of the guiding member provided with a vertical stud, a clip on said stud having a forwardly and downwardly 45 inclined face, and a yoke pivoted on the inclined face of the stud and having its branches slidably connected to said pendent members.

50 In testimony whereof I affix my signature, in the presence of two witnesses.
